US0D1019492S

(12) **United States Design Patent** (10) Patent No.: **US D1,019,492 S**
(45) Date of Patent: ** Mar. 26, 2024

(54) **ROTOR HUB**

- (71) Applicant: **Fisher & Paykel Appliances Limited**,
Auckland (NZ)
- (72) Inventors: **Russell Joseph Jackson**, Auckland
(NZ); **Zhang Quanbo**, Qingdao (CN)
- (73) Assignee: **Fisher & Paykel Appliances Limited**
(NZ)

(**) Term: **15 Years**

(21) Appl. No.: **29/822,555**

(22) Filed: **Jan. 10, 2022**

(51) LOC (14) Cl. **12-16**

(52) U.S. Cl.

USPC **D12/180**

CLAIM

The ornamental design of a rotor hub, as shown and described.

DESCRIPTION

FIG. 1 is a top perspective view of the rotor hub;

FIG. 2 is a bottom perspective view thereof;

FIG. 3 is a front view thereof;

FIG. 4 is a back thereof;

FIG. 5 is a left-side view thereof;

FIG. 6 is a right-side view thereof;

FIG. 7 is a top view thereof;

FIG. 8 is a bottom view thereof; and,

FIG. 9 is a cross-sectional view thereof.

The portions shown in dotted lines form no part of the claimed design.

1 Claim, 5 Drawing Sheets
